Primary Examiner — Sandra Snapp*Assistant Examiner* — Ieisha Price(74) *Attorney, Agent, or Firm* — Renner, Otto, Boiselle and Sklar, LLP(57) **CLAIM**

The ornamental design for an anchor, as shown and described.

DESCRIPTION

FIG. 1 is a top, left, front perspective view of an anchor showing my new design;

FIG. 2 is a top plan view thereof;

FIG. 3 is a left side elevation view thereof;

FIG. 4 is a bottom plan view thereof;

FIG. 5 is a right side elevation view thereof;

FIG. 6 is a front elevation view thereof;

FIG. 7 is a rear elevation view thereof; and,

FIG. 8 is a bottom, left, front perspective view thereof.

The broken line showing is for the purpose of illustrating portions of the article that form no part of the claimed design.

1 Claim, 8 Drawing Sheets(56)
